UNITED STATES PATENT OFFICE.

EUGENE GASSMANN, OF BROOKLYN, NEW YORK, ASSIGNOR TO EISEMANN MAGNETO CO., OF BROOKLYN, NEW YORK, A CORPORATION OF NEW YORK.

IGNITION DEVICE FOR INTERNAL-COMBUSTION ENGINES.

1,251,217.

Specification of Letters Patent. Patented Dec. 25, 1917.

Application filed March 14, 1917. Serial No. 154,742.

To all whom it may concern:

Be it known that I, EUGENE GASSMANN, a citizen of Germany, and a resident of the borough of Brooklyn, county of Kings, and 5 State of New York, have invented certain new and useful Improvements in Ignition Devices for Internal-Combustion Engines, of which the following is a complete specification.

10 My invention relates to ignition apparatus for internal combustion engines, and consists in devising a casing composed of two separable sections, wherein all component parts of the ignition device, including the 15 electrical conduits connecting the parts, are safely inclosed, and in so arranging the component parts of the ignition device in the two sections of the said casing, that they are made readily accessible by merely taking 20 apart the sections of the casing, which may be done without disconnecting any of the electrical conduits. One part, or section, of the casing constitutes the base, the other part is fitted thereon to cover the open top 25 of the base. The two parts, or sections, of the casing complement each other, and when joined form a compact unitary structure. The parts of the ignition device are arranged in two groups, each group being 30 housed in one of the two sections of the casing, and forming a unit complementary to the group of the parts housed in the other section. The two sections of the casing are locked together by only one spring latch, 35 and the arrangement affords an easy access to all parts of the ignition device by merely shifting the spring latch and then removing the cover part from the base of the casing. Thus all parts of the ignition device 40 may be readily examined, and any defective part repaired or replaced without disturbing or disconnecting any of the other parts.

My invention is illustrated in the accompanying drawings, wherein—

45 Figure 1 is a sectional view of my improved ignition device on line 1—1, indicated in Fig. 2;

Fig. 2 is a sectional view on line 2—2, indicated in Fig. 1, looking to the right; and

Fig. 3 is a similar view but showing the cover part of the unit removed (lifted) from the base.

Fig. 4 is a perspective view showing both parts assembled.

In these drawings, the numeral 4 designates the base of the casing, 5 the vertical front end extension thereof, and 13 designates the cover section. The driving shaft 6, whereon the cam 7, actuating the circuit breaker 8, is secured, is disposed lengthwise in the base 4 of the casing. A gear, or pulley 10, is set on the rear end of the shaft 6 for driving it by a transmission from the engine. The flanged plate 9, whereon the component parts of the circuit breaker 8 are mounted, is set turnably on the shaft 6, to enable the timing of the spark to be effected by shifting it on the shaft 6 accordingly. The electrical conduits 11 and 12, to and 65 from the circuit breaker, are made of sufficient length to enable the cover part 13 of the casing, to which the other terminals of the conduits 11 and 12 are connected, to be removed without requiring these conduits to 70 be disconnected. The conduits 11 and 12 fold into the interior of the base, as shown in Fig. 2. The stud 14 is journaled in the vertical extension 5 of the front end of the base 4; the gear 15, meshing with the gear 16 75 fixed to the shaft 6, and the distributor disk 17, are mounted on the stud 14 in the usual way.

In the end of the cover part 13 of the casing, adjoining the distributor disk 17 80 when the cover part of the casing is set in its place, the brushes 18 and 19 are set. The brushes 18 connect with the conduits 21 to the spark plugs of the cylinders of the engine; the brush 19 connects the distributor 85 disk 17 with the secondary winding of the induction coil 22, set, as shown in Figs. 2 and 3, in the cover part 13 of the casing, but separated and insulated from the distributor part thereof. The primary winding 90 of this coil 22 connects through the conduits 11 and 12 with the stationary and movable contacts of the circuit breaker and, through the conduits 26 and 27, with the battery. The ballast coil 24 is interposed in this connection to automatically regulate the volume 95 of electric current passing therethrough. The ballast coil 24 is supported on studs 28 and 29 on the underside of the cover part 13 of the casing in position to be within the 100 interior of the base 4, when the cover part 13 is set in its place thereon, whereas, when the cover part 13 is removed from the base, the ballast coil and its connections are 105 exposed. The condenser 31 is located in the 110

outer end of the cavity of the cover part 13 of the casing, and is separated from the induction coil 22 by the insulating partition 32.

When the cover part 13 of the casing is set in its place upon the base 4, its forward end engages with the rim 36 of the vertical extension 5 and the flange 39, extending along its sides and rear end, engages the rim 41 of the opening of the base 4. Thus the casing completely incloses all parts of the ignition device and protects it from injury by water, oil, dust, etc. The two sections of the casing are secured in this position by the spring latch 33, turnably mounted on the stud 35 set in the base 4 of the casing, and engaging with its correspondingly indented free end, as shown at 38, the pointed projection 37 on the cover part 13 of the casing. The spring latch 33 is set to press the cover part 13 against the vertical extension 5 of the base 4, and its engagement with the pointed projection 37 holds the flange 39 firmly upon the rim 41 of the base section of the casing, thus preventing accidental displacement of the cover part 13 by shock or vibration.

I claim as my invention:

1. An ignition device for internal combustion engines, comprising an induction coil, a condenser, a circuit breaker, a distributor, and the electrical conduits connecting the parts, arranged in a casing made of two parts, one part forming an open base and the other a cover therefor, each part of the casing containing some of the component parts of the ignition device, and the inter-part electrical conduits being completely inclosed in the casing by setting up the cover part upon the base, and means for securing the cover part of the casing to the base; substantially as herein shown and described.

2. An ignition device for internal combustion engines, comprising an induction coil, a condenser, a circuit breaker, a distributor, and the electrical conduits connecting the parts, all arranged in a casing made up of two sections fitted together to form a unitary structure, the electrical conduits connecting the component parts of the ignition device being arranged to enable the sections to be taken apart without disconnecting the electrical conduits, and means for securing together the sections; substantially as herein shown and described.

3. An ignition device for internal combustion engines, comprising a casing, com-

posed of two sections; a circuit breaker, a shaft, a gear fixed on the shaft, and means for actuating the circuit breaker, a stud, a gear meshing with the gear mounted on the driving shaft, and a distributor disk fixed thereto, mounted on the stud, arranged in one section; an induction coil, a condenser, brushes and electrical connections from the induction coil to the distributor, and from the distributor to the spark plugs of the engine, and to and from the source of electric current, arranged in the other section of the casing; electrical conduits connecting the induction coil and the circuit breaker, and means for securing the sections together; substantially as herein shown and described.

4. An ignition device for internal combustion engines, comprising a casing, composed of two sections; a circuit breaker, a shaft, a gear fixed on the shaft, and means for actuating the circuit breaker, a stud, a gear, meshing with the gear mounted on the driving shaft, and a distributor disk fixed thereto, mounted on the stud, arranged in one section; an induction coil, a condenser, brushes and electrical connections from the induction coil to the distributor, and from the distributor to the spark plugs of the engine, and to and from the source of electric current; a ballast coil and conduits connecting it with the induction coil, arranged in the other section of the casing; electrical conduits connecting the induction coil and the circuit breaker, and means for securing the sections together; substantially as herein shown and described.

5. A casing for an ignition device for internal combustion engines, comprising two sections, a base and a complementary part, fitted upon the base, each section of the casing being adapted to contain parts of the ignition device, and both together all parts of a complete ignition device, and their electrical connections, the two sections of the casing being adapted to completely inclose the parts and their electrical connections, when joined together, the parts of the ignition device being open to inspection when the sections of the casing are separated; and means for securing the sections of the casing together; substantially as herein shown and described.

EUGENE GASSMANN.
